UNITED STATES PATENT OFFICE.

JOHN Q. GRANT, OF LONGMONT, COLORADO.

ANTI-FRICTION ROLLER FOR WAGON-REACHES.

SPECIFICATION forming part of Letters Patent No. 349,644, dated September 21, 1886.

Application filed July 12, 1886. Serial No. 207,754. (No model.)

To all whom it may concern:

Be it known that I, JOHN Q. GRANT, of Longmont, in the county of Boulder and State of Colorado, have invented a new and useful Improvement in Anti-Friction Rollers for Wagon-Reaches; and I do hereby declare that the following is a full, clear, and exact description of the construction and operation of the invention, so that those skilled in the art could make and use the same therefrom, reference being made to the annexed drawings, making a part of this specification.

In wheeled vehicles the greatest amount of wear and friction occurs at the points of contact of the coupling-pole or reach and the sliding bar or sway-bar, and this friction soon wears away the parts, destroying either the bar or the reach, or both of them. The object of my invention is to reduce to the minimum this friction of the reach and bar.

To this end my invention consists in the combination of an anti-friction roller or of anti-friction rollers with the sway-bar and the reach, and also in certain other combinations and in minor constructions, as will be herein-after more fully specified, whereby the results above set forth may be attained.

In the accompanying drawings, Figure 1 is a top view. Fig. 2 is a bottom view. Fig. 3 is a view of a portion of the reach with the rollers applied thereto. Fig. 4 is a section taken on $x-x$, Fig. 3.

The same reference characters herein refer always to the same or similar parts.

The king-bolt is seen at A, securing the reach or coupling-pole D to the front axle, C, the hounds being shown at B B, to which is attached in the usual way the sway-bar or sliding bar H, on which bar is secured in any suitable manner a metallic bearing-plate, H'. It is here shown attached by means of screws. The bolster is seen at C' and the common fifth-wheel at G.

To the reach are attached two brackets, F F. These brackets are, as seen in Fig. 4, mortised or notched so as to receive the reach. They may be made of wood or metal, and in these brackets are journaled, free to revolve, the two anti-friction rollers C C. These rollers are made, as illustrated, of a double conical form, or swelled at the middle and tapering toward both ends. The brackets are attached to the

reach by means of screw-bolts I I, or even common screws. One object in view in using these notched brackets is to avoid cutting or mortising the reach itself, and thereby weakening the reach. Another and still more important object is to enable my improved anti-friction rollers to be applied to wagons already in use without any alteration whatever in the wagons themselves or their reaches. My improved anti-friction rollers, along with the brackets, can thus be put on the market as an article of manufacture and sold alone.

It is evident that by using my improved rollers the friction occasioned by turning and by all side motions and jostlings will be reduced to a minimum. By making the rollers swelled at the middle I have found by experiment that the friction is very much lessened, the rollers are very much less liable to bind, and more sure always to revolve or act. As soon as the sway-bar has run off the swell of one of them the swell of the other begins to act. It is evident that the use of one swelled or double conical roller alone would be within the scope of my invention; but I prefer two, as more easy of application to the reach and more satisfactory in action. It might be possible to apply the rollers to the slide or sway bar, but not desirable.

These rollers I make preferably of steel, malleable iron, or other metal; but it is evident that any hard durable substance—such as wood, hard rubber, &c.—might be used.

Having thus described my invention, what I desire to secure by Letters Patent of the United States and claim as new is—

1. The combination of a wagon-reach, a pair of brackets notched so as to fit the said reach, and in which are journaled so as to be free to rotate a pair of rollers with the sway-bar, substantially as and for the purpose set forth,

2. The combination of the coupling-pole of a wagon, two brackets having notches adapted to fit the reach, bolts securing said reach and brackets together, and a pair of double conical or centrally-swelled rollers journaled in said brackets with the slide-bar of a wagon, substantially as and for the purpose set forth.

3. The combination of a wagon-reach or coupling-pole, a pair of brackets secured to said reach or pole and one or more double-coni-

cal or centrally-swelled rollers supported in said brackets with a slide or sway bar of a wagon, substantially as described.

4. As a new article of manufacture, a pair of brackets adapted to be fitted to the reach of a wagon, and one or more double-conical or centrally-swelled rollers adapted to be journaled therein, substantially as described, and for the purpose set forth.

In testimony that I claim the above I have to hereunto subscribed my name, in the presence of two witnesses, this 7th day of July, A. D. 1886.

JOHN Q. GRANT.

Witnesses:

B. L. CARR,
F. E. HARTMAN.

Correction in Letters Patent No. 349,644.

It is hereby certified that Letters Patent No. 349,644, granted September 21, 1886, upon the application of John Q. Grant, of Longmont, Colorado, for an improvement in "Anti-Friction Rollers for Wagon-Reaches," was erroneously issued to said Grant; that the said Letters Patent should have been issued to said Grant and *Frank P. Secor and George T. Dell, of same place*, said Secor and Dell being assignees of one-half interest in said invention; and that the said Letters Patent should be read with this correction therein that the same may conform to the record of the case in the Patent Office.

Signed, countersigned, and sealed this 5th day of October, A. D. 1886.

[SEAL.]

H. L. MULDROW,
Acting Secretary of the Interior.

Countersigned:

R. B. VANCE,
Acting Commissioner of Patents.
